UNITED STATES PATENT OFFICE.

IDA S. GRUNDLOCK, OF PHILADELPHIA, PENNSYLVANIA.

DESIGN FOR A SOUVENIR EMBLEMATIC GATE.

Application filed September 21, 1925. Serial No. 14,842. Term of patent 3½ years.

To all whom it may concern:

Be it known that I, IDA S. GRUNDLOCK, a citizen of the United States, residing at Philadelphia, in the county of Philadelphia and State of Pennsylvania, have invented a new, original, and ornamental Design for Souvenir Emblematic Gate, of which the following is a specification, reference being had to the accompanying drawing, forming part thereof.

The figure is a perspective view of a souvenir emblematic gate, showing my new design.

I claim:

The ornamental design for a souvenir emblematic gate, as shown.

IDA S. GRUNDLOCK.
